CANOPY DOME

Alvin E. Miller, Hamilton, Ohio, assignor to Pease Wood-work Company, Hamilton, Ohio, a corporation of Ohio

Filed June 8, 1959, Ser. No. 56,248

Term of patent 14 years

(Cl. D13—1)

FIG. 1.

FIG. 2.

FIG. 3.**FIG. 4.**

Figure 1 is a top plan view of a canopy dome embodying my new design,

Figure 2 is a front elevation of the canopy dome,

Figure 3 is a rear elevation of the canopy dome, and

Figure 4 is a side elevation of the canopy dome taken from the right side of Figure 2.

The characteristic features of the design reside in the generally triangular configuration as viewed from above, and in the fact that the sides of said triangle, when viewed in elevation, appear as arches extending between the apices of said triangle.

I claim:

The ornamental design for a canopy dome, as shown and described.
